REGULATION OF SUPERHEAT AND FEED
WATER TEMPERATURESPierre Frederic Pourchot, Belfort, France, assignor
to The La Mont Corporation, New York, N. Y.Application March 6, 1941, Serial No. 381,992
In Germany November 24, 1939

1 Claim. (Cl. 122—480)

The present invention relates to steam generators and particularly to means for regulating the temperature of feed water and superheated steam.

It is known to regulate superheat temperature by means of dampers and to have steaming surface in parallel with the superheater surface or in a by-pass and to have economizer surface following both of these surfaces. However, in this arrangement operation of the dampers does not result in the simultaneous regulation of the temperature of both the feed water and superheated steam because depending upon the position of the dampers, there will be a reduced impingement of heat in one of the passes and a corresponding increase of impingement of heat of the by-pass or parallel pass. Superheated steam temperature may be regulated by this means, but the feed water temperature remains entirely unaffected. The feed water temperature varies in accordance with the changes in boiler rating resulting in material disadvantages in that it is not possible to completely utilize the best temperature drop in the economizer and, consequently, that temperature stresses may occur in the boiler drum.

The present invention avoids these difficulties in a simple way. The steam generator has an offtake duct divided into two parallel gas passes by means of a solid tube wall. In one pass superheater surface and the economizer are placed, and the steaming surface is located in the other of said passes. With this arrangement of the heating surfaces the operation of dampers controlling the passes regulates the superheated steam temperature and the feed water temperature simultaneously. By placing the economizer immediately behind the superheater in the direction of gas flow and parallel to steaming surface the economizer becomes subject to the control of the dampers for the superheater pass and its by-pass. As the temperature characteristics of the superheater and economizer are substantially alike, the feed water temperature rises and falls in accordance with the boiler rating like the superheat. By maintaining the superheat temperature as nearly constant as possible, the feed water temperature is simultaneously maintained constant.

Heretofore it was customary to heat feed water

to a temperature substantially below the boiling point so as to avoid the formation of steam at peak loads as a result of exceeding the boiling temperature, which was undesirable. Since, according to the invention, the feed water temperature may be maintained constant, it now becomes possible to approach the boiling temperature in heating the feed water without causing steam formation by load changes.

As a further advantage of the invention it will be noticed that the dampers are arranged in a low temperature zone so that damage from burning the dampers is unlikely. When the boiler is of the forced circulation type it is an easy matter to separate the two parallel gas passes by forming a solid wall built out of tubes of the heat absorbing surface.

The invention is described more fully hereafter in conjunction with the single figure of the accompanying drawing which diagrammatically represents a forced circulation boiler. The down-flow gas pass is divided into two parts by a solid tube wall 10 thus forming two parallel gas passes. In one of these gas passes steaming surface 11 is arranged. In the other pass superheater surface 12 and economizer surface 13 are located. Beyond these heating surfaces in the direction of gas flow are control dampers 14 for each gas pass. For further extraction of heat from the gases there is an air preheater 15. The advance heating surface 16 may be made as large as desired. As shown in the illustration, the separating wall 10 and the steaming surfaces 11 and 16 may be made into a common tube coil which is supplied by the distributor header 17 and delivers directly into the steam and water drum 18. The feed water temperature is simultaneously regulated by means of the setting of dampers 14 in dependence upon the steam temperature.

What I claim is:

A steam generator having an offtake duct for flue gases; steam generating tubes arranged to form a solid wall dividing said offtake duct to form two parallel gas passes; a superheater and an economizer located in one pass; steam generating elements disposed in the other pass; and damper means for controlling gas flow in said passes.
